ESCUOTCHEON PLATE FOR AN ELECTRICAL DEVICE

Giovanni Cali, Piazza del Liberty 8, Milan, Italy

Filed Nov. 23, 1971, Ser. No. 201,622

Term of patent 3½ years

Int. Cl. D8—09; D13—03

U.S. Cl. D8—188

FIG. 1

FIG. 2

FIG. 3

FIG. 4

FIG. 5

FIG. 6

FIG. 1 is a front elevational view of my escutcheon plate for an electrical device;

FIG. 2 is a side elevational view (both sides are identical);

FIG. 3 is an end elevational view (both ends are identical);

FIG. 4 is a longitudinal section view taken along line 4—4 of FIG. 1;

FIG. 5 is a rear elevation view; and

FIG. 6 is a transverse sectional view taken along line 6—6 of FIG. 5.

I claim:

The ornamental design for an escutcheon plate for an electrical device, as shown.
